(57) **CLAIM**

The ornamental design for a racket drum, as shown and described.

DESCRIPTION

FIG. 1 is a perspective view of a racket drum showing my new design;

FIG. 2 is a front elevational view of the racket drum as shown in FIG. 1;

FIG. 3 is a side view of FIG. 2;

FIG. 4 is a top view of FIG. 2;

FIG. 5 is a bottom view of FIG. 2; and,

FIG. 6 is a rear elevational view of FIG. 2.

The broken lines showing a team logo on the front side of the racket drum and the team slogan on the rear side of the racket drum are for illustrative purposes only and form no part of the claimed design.
